Des. 184,835

PAGE 3

Figure 1 is a perspective view of a drill press showing my new design;

Figure 2 is a perspective view thereof as seen from the opposite side and top of Figure 1;

Figure 3 is a fragmentary view slightly in perspective thereof as seen from the front of Figure 1; and

Figure 4 is a perspective view thereof as seen from the rear of Figure 1.

I claim:

The ornamental design for a drill press, as shown.
